UNITED STATES PATENT OFFICE.

ALBERT EMACK, OF CALAIS, MAINE.

LAMP-BURNER.

1,124,880.

Specification of Letters Patent. Patented Jan. 12, 1915.

Application filed May 2, 1914. Serial No. 835,986.

To all whom it may concern:

Be it known that I, ALBERT EMACK, a subject of the King of Great Britain, and a resident of Calais, in the county of Washington and State of Maine, have invented 5 certain new and useful Improvements in Lamp-Burners; and I do hereby declare the following to be a full, clear, and exact description of the invention, such as will enable others skilled in the art to which it 10 appertains to make and use the same, reference being had to the accompanying drawings, and to the letters and figures of reference marked thereon, which form a part 15 of this specification.

This invention relates to new and useful improvements in lamp burners and comprises a simple and efficient device consisting of rubber tubes adapted to fit over the 20 fingers which hold the chimney, the tubes being provided with metallic tips which are fastened to the fingers and afford means for protecting the tubes and guiding the chimney as it is placed upon the burner.

25 The invention comprises various details of construction, combinations and arrangements of parts which will be hereinafter fully described, shown in the accompanying drawings and then specifically defined 30 in the appended claims.

I illustrate my invention in the accompanying drawings, in which:

Figure 1 is a side elevation of a burner made in accordance with my invention. 35 Fig. 2 is an enlarged detail view of one of the tubes removed from a finger, and Fig. 3 is a sectional view on line 3—3 of Fig. 1.

Reference now being had to the details 40 of the drawings by letter, A designates a burner of the usual wick type for lamps which has resilient fingers B. Tubes, des- ignated by letter D, are fitted over each fin-

ger and at the upper end of each tube is a metallic tip, designated by letter E, which is tapering as shown and which is fastened 45 to the finger by means of an upset part of the tip engaging the aperture in said finger, thus securely holding the same in place. Said tube being of rubber will conform to the outwardly flaring portion of the finger, 50 while the inner face of the tip will present a surface against which the lower end of the chimney is adapted to contact.

By the provision of an attachment to the burner as shown and described, it will be 55 noted that a simple and efficient means is afforded whereby the rubber tube will prevent the chimney from accidentally falling off, the tip also protecting the rubber and, by upsetting a portion thereof, forms a 60 means for clamping the device upon the finger or the stake of the burner.

What I claim to be new is:

1. In combination with a burner having 65 resilient chimney engaging fingers, rubber tubes, each fitted over a finger, a metallic tip fastened to the upper end of each tube, a portion of said tip being upset to frictionally hold the tip and tube in contact 70 with the finger.

2. In combination with a burner having resilient chimney engaging fingers which are slotted near their upper ends, rubber tubes fitted over said fingers, a metallic tip surrounding the upper end of the tube and 75 tapering, a portion of the tip being upset and holding a portion of the tube in the slot of the finger.

In testimony whereof I hereunto affix my signature in presence of two witnesses.

ALBERT EMACK.
